DORF, GERMANY

BREECH CLOSURE

Application filed August 13, 1930, Serial No. 475,056, and in Germany September 14, 1929.

This invention relates to a breech closure, in which the firing mechanism is placed under tension by the movement of the closing lever before the beginning of the closing movement of the breech. In prior closures of this type, the breech block can move during the movement of the opening lever, which tensions the firing mechanism, but this may be dangerous when the tensioning of the firing mechanism is repeated, as when a misfire has occurred.

The invention obviates this defect and provides a breech closure, in which, in case of a misfire, a retensioning of the firing mechanism by the closing lever is possible, without any danger of an unintentional opening of the breech being thereby occasioned as, for example, by the resistance of the firing-pin spring. To this end, the breech is locked in its closed position by an escapement lock, which is automatically thrown out by the recoil of the barrel after firing. Furthermore, a second locking device is provided, which releases the closed breech only after an opening movement of the closing lever, which exceeds that for effecting the complete tensioning of the firing pin. This second lock secures the breech against being opened during the movements of the barrel in closing, after the throwing out of the escapement mechanism, and, therefore, the breech can only move, when it is to be opened, after the full tensioning and locking of the firing mechanism, so that a premature advance of the latter during the movement of the breech, which might be injurious, is prevented.

In the drawing, an embodiment of the invention applied to a horizontal wedge breech closure is represented.

40 In the drawings:

Figure 1 is a longitudinal section through the barrel and breech,

Fig. 2 is a plan of the same with the base piece partially cut away,

Fig. 3 is an elevation of the base piece from the rear,

Fig. 4 is a section through the base piece and the escapement mechanism, taken on line 50 A—A of Fig. 3,

Fig. 5 is a side view of a portion of Fig. 2 with the breech latch in section, and

Fig. 6 is a side view partly in section showing the escapement mechanism of Fig. 4, looking from the side.

55 In the base portion a_1 of the barrel a is mounted the breech block b , movable transversely horizontally in guideways. It receives the firing-pin c , which is movable in the direction of the barrel axis under the influence of the spring c_1 , the front end of said pin carrying the firing point and being provided with a lateral shoulder c_2 . In front of this shoulder lies the lug d_1 of a tensioning shaft d , rotatable in the breech block b and carrying a lever d_2 , which can swing horizontally in a recess b_1 of said block. The free end of lever d_2 is pivotally connected, by the latch f , with a second lever e_2 , mounted on a shaft e , rotatable in the base piece a_1 by means of a hand lever e_1 against spring pressure.

60 In accordance with the invention, the breech block is locked in closed position at one time by an escapement mechanism, automatically disengaged by the recoil of the barrel. To this end, a bolt l is mounted in the breech block b , (Figs. 4 and 6) so as to be movable in the direction of movement of the barrel. Said bolt remains firmly connected with the bushing l_1 , during the recoil of the barrel, in consequence of its inertia and against the action of the spring l_2 , so that a latch pin i , mounted at right angles to the direction of movement of said bolt and acted 65 upon by spring i_1 , engages in a notch l_3 of bolt l . The bushing l_1 , fast on the bolt l , is thereby held back with its nose l_4 out of the latch groove b_4 of the base piece a_1 and in a recess b_3 of the breech block. The latch pin i has a bevel surface i_2 near its top, with which it projects into the path of the opening lever f when the escapement latch device, l, l_1, l_4 is maintained out of engagement. The lever f forces it out of locking position after a certain opening movement, so that the escapement mechanism is released and is moved back by spring l_2 until its nose l_4 enters the groove in the base piece a_1 . During the further opening movement of the breech 70 75 80 85 90 95

block, the nose l_4 slides in said groove until it comes out of the same and is moved further back for a limited distance by the spring l_2 . By the closing of the breech, the laterally beveled nose l_4 is forced forwardly from the groove in the base piece a_1 , against the action of spring l_2 , and slides then along said groove again, in correspondence with the closing movement of the breech, until it springs into the groove b_4 , when the breech b is closed, and locks the same.

In addition to the escapement lock, a second locking mechanism is provided to prevent a premature opening of the closed breech. In the groove of the base piece a_1 , a bolt g is provided (Figs. 1 and 5), which is acted upon by spring g_1 and which, by springing into a notch in the closed breech block, locks the latter against opening movement. The upper part of the locking bolt g projects into the guideway, formed by the recess b_2 (Fig. 2) of the nose f_1 of the link f , so that the bolt g is disengaged by the movement of said link in the opening operation.

In describing the operation, it is assumed that the parts are in the closed position, in which the breech block is locked by the bolt g as well as by the escapement l . If after the operation of the trigger, not shown, the gun has not fired, the firing-pin c is retensioned by swinging the opening handle e_1 in the direction of the arrow in Fig. 2, through the transmission members e_2, f, d_2 , shaft d and nose d_1 . This moves lever d_2 into the recess b_1 of the breech block b and limits the tensioning movement by striking against the vertical end surface b_5 of the recess b_1 . Shortly before, nose f_1 of the connecting member f disengages the bolt g , while the escapement l, i , prevents the opening of the breech. After the tensioning of the firing-pin, the opening lever e_1 is returned to its initial position by a spring, not shown, and the connecting lever f thereby releases the bolt g so that it can engage the breech block. Therefore, in case of a misfire, repeated tensioning of the firing-pin can be had by actuating the opening handle, while the breech is still locked and secured against opening. An opening of the breech is then only possible where the escapement mechanism is released by hand.

If the gun misses fire in normal operation, the escapement mechanism is automatically unlocked by the recoil of the barrel. But the breech then remains locked by the bolt g , until the firing-pin is placed under tension by swinging the opening handle e_1 in the direction of the arrow and, after the nose d_1 of the tensioning shaft d slides off the shoulder e_2 , is held as usual by the catch bolt. In the further swinging of said handle, the nose f_1 of the link f forces the bolt g back and the lever d_2 , now bearing on the surface b_5

of the breech block, forces the unlocked breech b into the loading position. By swinging back the opening lever e_1 , after the loading, the breech b is brought back into the closed position, whereupon the bolt g and the escapement l again come into their locking positions.

We claim as our invention:—

1. A breech closure for guns, comprising a breech; a breech lever; a firing mechanism; an escapement mechanism for locking the breech against opening, said mechanism being automatically released during recoil of the gun; and a locking device adapted to also lock the breech against opening, said locking device being released only by an opening movement of the breech lever exceeding the tensioning of the firing mechanism. 70

2. A breech closure for guns, comprising a barrel having a base portion; a breech mounted in said base portion; a breech lever mounted on said portion; a firing mechanism in said breech; an escapement mechanism mounted in said breech for locking the breech against opening, said mechanism being automatically released during recoil of the gun; and a locking device in the barrel adapted to also lock the breech against opening, said locking device being released only by an opening movement of the breech lever exceeding the tensioning of the firing mechanism. 85

3. A breech closure for guns, comprising a breech and breech lever mounted on the gun; a tensioned firing mechanism; means for locking the breech against opening and being automatically released during recoil of the gun; and further means adapted to also lock the breech against opening and being released only by an opening movement of the breech lever exceeding the tensioning of the firing mechanism. 100

In testimony whereof, we affix our signatures.

FRITZ HERLACH.
HANS LUDWIG.
